UNITED STATES PATENT OFFICE.

WILLIAM FISKE STRANGMAN, OF SALEM, MASSACHUSETTS.

MASSAGING DEVICE FOR THE GUMS.

1,002,468.

Specification of Letters Patent. Patented Sept. 5, 1911.

Application filed June 16, 1910. Serial No. 567,195.

To all whom it may concern:

Be it known that I, WILLIAM FISKE STRANGMAN, a citizen of the United States, residing at Salem, in the county of Essex and State of Massachusetts, have invented certain new and useful Improvements in Massaging Devices for the Gums; and I do declare the following to be a full, clear, and exact description of the invention, such as will enable others skilled in the art to which it appertains to make and use the same.

This invention relates to an improved implement for massaging the gums and tissues around the teeth.

15 The object of the invention is to provide a simply constructed massaging device constructed to readily contact with the various tissues around the teeth whereby they may be thoroughly massaged.

20 With this and other objects in view, the invention consists of certain novel features of construction, combination and arrangement of parts as will be more fully described and particularly pointed out in the 25 appended claim.

In the accompanying drawings: Figure 1 is a perspective view of this improved massaging device; Fig. 2 is a bottom plan view thereof; and Fig. 3 is a side elevation with 30 parts broken away.

In the embodiment illustrated a soft rubber gum engaging member or head 1 is shown, preferably curved longitudinally throughout its length providing a concave 35 inner face 2 having a longitudinally extending groove 2^a at its free end and a convex outer face 3, each of said faces being provided with a plurality of transversely extending corrugations, as 4, the projections 40 or teeth 5 formed by said corrugations being designed to perform the massaging operation when passed over the gums. This

head or tip 1 is preferably tapered toward its longitudinally grooved end and is secured at its opposite end to a handle member 6 in any suitable or desired manner, the means here shown comprising a short steel rod 7 having one end tapered and embedded in the rubber head 1 and the other end is secured to the handle member 6 whereby the 45 connection with the handle is reinforced and strengthened, preventing danger of breakage at this point. The tapered end of said head is designed to be used in a rather closely confined space and moved laterally 50 with the handle 6 held vertically, hence it is grooved longitudinally as shown at 2^a to provide a multiplicity of teeth or projections at this point to produce an improved therapeutic effect. It will be obvious that 55 this tip or head 1 may be made in a variety of sizes with slight variations in shape and attached to handles of any desired form.

I claim as my invention:

A massaging device for the gums around the teeth comprising a flexible head with a concave inner face and a convex outer face, said head having a tapered terminal, the convex outer face having continuous transverse teeth thereon, and the concave face 70 having transverse teeth extending part way of its length, a plurality of oppositely disposed teeth upon its tapered portion, a metal rod having a tapered end embedded in the end of said head, and a detachable 75 handle.

In testimony whereof I have hereunto set my hand in presence of two subscribing witnesses.

WILLIAM FISKE STRANGMAN.
